Primary Examiner — T. Chase Nelson*(74) Attorney, Agent, or Firm* — Ostrolenk Faber LLP(57) **CLAIM**

The ornamental design for a hooded backpack, as shown and described.

DESCRIPTION

FIG. 1 is a perspective view of the hooded backpack;
FIG. 2 is a rear elevational view of the hooded backpack;
FIG. 3 is a front elevational view of the hooded backpack;
FIG. 4 is a left side view of the hooded backpack;
FIG. 5 is a right side view of the hooded backpack;
FIG. 6 is a top plan view of the hooded backpack; and,
FIG. 7 is a bottom plan view of the hooded backpack.
The broken lines in the drawings illustrate environmental structure and form no part of the design.
